(57) **CLAIM**

The ornamental design for an oral care implement, as shown and described.

DESCRIPTION

FIG. 1 is a front perspective view of an oral care implement of the new design;

FIG. 2 is a rear perspective view thereof;

FIG. 3 is a front view thereof;

FIG. 4 is a rear view thereof; a

FIG. 5 is a left side view thereof;

FIG. 6 is a right side view thereof;

FIG. 7 is a top view thereof; and,

FIG. 8 is a bottom view thereof.

The broken lines illustrating portions of the oral care implement form no part of the claimed design. The dot-dash broken lines define the bounds of the claimed design and form no part thereof.

1 Claim, 4 Drawing Sheets
